UNITED STATES PATENT OFFICE.

WILLIAM C. CODMAN, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A COFFEE-POT.

No. 40,156.

Specification for Design.

Patented July 20, 1909.

Application filed May 14, 1909. Serial No. 496,086. Term of patent 14 years.

To all whom it may concern:

Be it known that I, WILLIAM C. CODMAN, a subject of the King of Great Britain, residing at Providence, in the county of Providence and State of Rhode Island, have invented a new, original, and ornamental Design for a Coffee-Pot, reference being had to the accompanying drawing.

The figure in the drawing is a view of one side of a coffee pot, showing my design.

I claim—

The ornamental design for a coffee pot, as shown.

WILLIAM C. CODMAN.
